UNITED STATES PATENT OFFICE

FREDERICK F. HASKELL, OF ARLINGTON, MASSACHUSETTS, ASSIGNOR TO APEXON COMPANY, OF JAMAICA PLAIN, MASSACHUSETTS, A CORPORATION OF MASSACHUSETTS

METAL WINDOW SCREEN

Application filed December 18, 1928. Serial No. 326,873.

This invention relates to metal window screens. Some of the desirable characteristics of a metal window screen are that it should be light in weight and the sides of the frame should have as small a cross-sectional area as possible consistent with the strength and rigidity required of the frame.

5 Metal window screens are now frequently made with hollow sides, that is, the sides of the frame are formed by bending or folding sheet metal into the desired shape. Such a frame can be made relatively light and it has the desired stiffness and rigidity but the cross-sectional area of the frame is necessarily 10 of dimensions larger than desirable. A window screen having a frame with solid sides would be unduly heavy if made of iron, bronze or similar metal.

My invention has for its object to provide 20 a novel metal window screen which has the desirable characteristics of being both light in weight and of the required rigidity and stiffness. I secure a window screen of light weight by making the frame of a light weight 25 metal such as aluminum and I secure the desirable small cross-sectional area of the sides of the frame by making said sides solid.

The four sides of the frame are integrally connected at the corners and in order to give 30 added stiffness and rigidity to the frame so that it will not warp or twist I so construct the frame that the material at the corners thereof is harder and more rigid than at other parts of the frame. In a rectangular 35 frame, such as the frame for a window screen, the resistance to the warping or twisting of the frame is derived largely from the metal at the corners of the frame and in my improved frame the metal at these points is made stiffer 40 and more rigid than in the body of the sides of the frame.

I thereby produce a window screen which is light in weight, in which the sides of 45 the frame have a relatively small cross-sectional area and yet which is stiff and rigid.

In order to give an understanding of the invention I have illustrated in the drawings a selected embodiment thereof which will 50 now be described after which the novel

features will be pointed out in the appended claims.

Fig. 1 is a view of a window screen embodying my invention;

Fig. 2 is an enlarged detail view of one 55 corner of the screen;

Fig. 3 is a sectional perspective view of the screen embodying my invention;

Fig. 4 is a perspective view showing one 60 of the handles.

The window screen comprises the frame 1 having the four sides 2 which are integrally connected at the corners 3, and the wire screen 4 which is attached to the frame 1. In the construction herein shown the sides 65 2 of the frame 1 are provided with grooves 5 in which the edges 6 of the wire screen 4 are received. These edges 6 are locked in the grooves by means of locking keys 7 which are forced into the grooves 5.

70 The sides 2 are made of aluminum or aluminum alloy and are solid in cross section. A window screen made of an aluminum product has the advantage of being light in weight and by making the sides 2 solid they can be 75 made of the desirable small cross-sectional area.

According to my invention, the corners 3 of the frame 1 are specially treated so as to increase the strength of the frame at these 80 points. This treatment is in the nature of a heat treatment. When aluminum alloy containing small amounts of one or more of such ingredients as copper, manganese, magnesium or silicon, is heated to approximately welding temperature and then is cooled, its stiffness and rigidity is increased, the increase continuing for several days after the heating and cooling operation.

85 In making the window screen in accordance with my invention I weld together the four sides of the frame at the corners and the welding operation is so carried out as to produce the added stiffness and rigidity at the corners as above described. A screen frame 90 thus made is one which is light in weight and the sides of which have small cross-sectional area but which is nevertheless of sufficient 95 stiffness and rigidity at the corners so that it will not twist or warp.

In the drawings the portion of the material of the screen at the corners thereof which is made stiff and rigid is indicated by the stipled area 14.

- 5 The window screen is provided with suitable handles. These are shown at 8 and each is provided with a handle portion 9 and the two arms 10. The arms and handle portion may be made from a blank of sheet metal 10 which is shaped to form the tubular handle portion 9 and arms 10. Each arm is formed at its lower end with a circular portion 11 which sets in a recess 12 formed in the bottom rail of the frame so that the arms will come 15 flush with the face of the frame. These arms are secured to the frame by means of rivets 13 which extend into the grooves 5 and are, therefore, concealed on the front of the frame by the locking bead 7.
- 20 In forming the handle the blank is bent so that the tubular handle portion 9 will stand inside of the arms 10 so that the handle will present no obstacle which extends outwardly from the back face of the screen. By means 25 of this construction the handle presents no obstruction to the free up and down movement of the screens.

I claim.

1. A window screen comprising a frame of 30 aluminum alloy having integrally-connected sides and a wire screen secured to said sides, the material of the frame at the corners thereof being stiffer and more rigid than at the other portions of the frame.
- 35 2. A window screen comprising a metal frame having integrally-connected sides which are solid in cross section and each of which is grooved, a wire screen having its edges received in the grooves, locking keys 40 occupying the grooves and retaining therein the edges of the wire screen, handles for the screen each comprising a handle portion and arms of sheet metal extending therefrom, each arm terminating in a circular foot portion, the face of the screen opposite the grooved face being provided with circular recesses to receive said foot portions, which recesses are so positioned that the centers thereof are directly opposite the groove, and rivets 45 extending centrally through the feet for connecting said feet to the screen frame, one end of each rivet occupying the groove in the frame and thus being concealed by the locking key.
- 50 55 3. A window screen comprising a frame of aluminum alloy, the four sides of which are welded together at the corners, the material of the frame at the corners where the sides are welded together being stiffer and more rigid than at other portions of the frame.

In testimony whereof, I have signed my name to this specification.

FREDERICK F. HASKELL.
